UNITED STATES PATENT OFFICE.

RAYMOND AUGUSTE DORNÈS, OF NEW YORK, N. Y., ASSIGNOR TO DORWIN MANUFACTURING COMPANY, OF PHOENIX, ARIZONA, A CORPORATION OF ARIZONA.

PROCESS AND APPARATUS FOR REFINING OILS.

Application filed November 27, 1912, Serial No. 733,774. Renewed September 13, 1920. Serial No. 410,009.

To all whom it may concern:

Be it known that I, RAYMOND AUGUSTE DORNÈS, a citizen of the Republic of France, residing in the borough of Manhattan, city, county, and State of New York, have invented certain new and useful Improvements in Processes and Apparatus for Refining Oils, of which the following is a specification.

10 This invention relates in general to the refining of oils, and to the production of useful fluids or gases therefrom. It includes certain processes and apparatus which will hereinafter be more specifically referred to. The invention is especially directed to the refining of crude hydrocarbon oils, and will be explained with more particular reference to such oils with the understanding that it is also applicable for 20 use in other connections.

The process or processes by which I arrive at the various hydrocarbon products are simple, easily worked, and accurately manipulated irrespective of outside temperatures. The apparatus which I prefer to employ for these purposes is simple and economical in construction, and practically self-cleansing. The operation provided by my invention may be described as a practically continuous one, and the various products designed to be manufactured may be drawn from various points in the apparatus, usually in their pure and uncontaminated form, so that no further distilling or purifying process is required.

In general according to my invention, in its most complete and efficient form, I take crude oil, either in its present commercial form or even shale oil or other oils which have heretofore been practically uncommercial products, and heat the same in such manner that the dirt, minerals and other impurities are successively dropped out of the oil so that the latter finally becomes substantially purified. Upon reaching its vaporous form I inject into the body of vaporous oil steam at a proper temperature and the combined steam and oil are further heated and pass through a succession of expansive steps until a pure mixture of steam and oil vapors is produced. During this operation the temperatures are so regulated that a fixed hydrocarbon gas is not formed. However, ac-

cording to my invention the temperature 55 may be increased to form such a gas, if a hydrocarbon gas is the end aimed at. In such case I can produce a hydrocarbon gas of high illuminating power which is almost entirely devoid of carbon monoxide. In 60 the manufacture of hydrocarbon products other than fixed gases, however, the temperature is so regulated that the fixation point is not reached, and the mixture of steam and oil vapors is passed to a succession of what may be termed condensers. These condensers, however, are preferably not of the ordinary construction or operation. Each is preferably so constructed that it has what may be termed hot and 70 cool zones which may be maintained accurately by the use of a steam jacket and a water jacket. The entering mixture of steam and oil vapor from the generator passes through the first condenser and in 75 such condenser is condensed out that product whose liquefaction point corresponds to the cooler zone, while those products which are still gaseous at the temperature of the cooler zone pass out to a second condenser 80 where the temperatures of both zones are somewhat lower, depending upon the product to be obtained. A similar action takes place in the second condenser and in the third, fourth and succeeding condensers. At 85 each condenser a definite product is obtained which is correlative and corresponds to the temperatures maintained.

The invention also includes the apparatus which has been provided by me to carry 90 into effect my invention and certain other features of improvement which will be hereinafter pointed out.

Referring to the drawings, wherein I have illustrated one form of apparatus 95 which is suitable for the purpose,—

Fig. 1 is a front elevation of the vaporizer which I prefer to employ, the front plate being removed, and some of the parts being shown in section.

Fig. 2 is a vertical section of Fig. 1 taken on the line 2—2 in this figure, and on the line 2—2 in Fig. 4.

Fig. 3 is a horizontal section of Fig. 1 taken on the line 3—3, the top wall being 105 removed.

Fig. 4 is a similar view taken on the line 4—4 in Fig. 1;

Fig. 5 is a vertical section taken on the line 5—5 in Fig. 1 and looking to the right;

Fig. 6 is a horizontal section of Fig. 1 on the line 6—6;

Fig. 7 is a detail view of one of the deflector nozzles;

Fig. 8 is a central vertical section of one of the automatic residuum valves;

Fig. 9 is a central vertical section partly 10 in elevation of one of the condensers.

Before beginning a detailed description of the particular features of the invention, I would say, briefly, that the crude oil or other starting substance is fed into the generator A (Fig. 1) is purified and relieved of most if not all of the impurities, and the product from generator A, which consists preferably of purified hydrocarbons and steam, is fed to the condenser (Fig. 9) 20 wherein the heavier hydrocarbons may be deposited and successively to other condensers, in each of which there is abstracted from the product of a lighter hydrocarbon, or to be more precise a hydrocarbon whose 25 liquefaction point is lower, due regard being had to the pressures employed. Obviously these may be changed in effect, but it is more convenient and economical to obtain products of successively lower liquefaction 30 point, since by this means the heat which is retained in the mixture after leaving each successive still is utilized.

As the crude oil which has been preliminarily treated is first passed through the 35 generator, this device will be first described.

Referring to Fig. 1, the generator A comprises a shell or casing preferably mounted upon a brick foundation *a* having side walls *b*, *b'*, a fire brick arched roof *c* and sheet 40 metal or brick front and rear walls. Briefly speaking, the generator may be divided into a water heating or steam making section, an oil heating or vapor section and a super-heating section for the mixed oil 45 vapors and steam.

The water heating section preferably comprises a vertical water chamber *d* which preferably is formed in the side wall *b* of the generator. To this end the side wall *b* is 50 formed of sheet metal plates spaced apart to form a chamber between them, this chamber preferably extending nearly if not quite the full length and height of the generator.

Feed water is admitted by valve *e* which 55 fills the chamber *d* and the various tubes to be described until the water line *f* is reached. Connected to the inner wall of the chamber *d* are a series of water heating tubes or 60 coils *g*, *g'*, *g''* etc. Of these coils *g* (Fig. 2) extend nearly to the opposite side of the generator, and return to the chamber *d*. The tubes rest upon narrow fire-brick walls 65 *h*, *h'* which constitute in effect the sides of the fire-box. Under certain conditions the

generator may be operated by ordinary coal or other fire, but it is preferred to use a liquid fuel burner *C*. In the construction shown the coils *g* extend across the fire-box immediately above the burner *C*, and resting upon the walls *h*, *h'* form a support for the

superheating sections for the oil vapor and steam which are to be described. On the return legs of the coils *g*, *g'* the ends thereof

are bent upwardly so that a circulation of 70 water through these coils is attained.

Above the coils *g* are a series of short tubes *g''* which extend inwardly from the inner wall of the water chamber *d*, and are prefer-

ably staggered in their arrangement, as best 75 seen in Fig. 2. Above the series of tubes *g''* are preferably arranged a series of similar sealed tubes *g'*, which are progressively

longer than the tubes *g''* so that they extend further toward the middle of the generator. The top coils *g''* are preferably extended 80 completely across the upper part of the generator and have return legs which are best

shown in Fig. 3, such return legs re-entering 85 the water chamber *d* at a point considerably

above the forward legs of the coil. The effect of this construction is that water in 90 the chamber *d*, tubes and coils becomes pro-

gressively hotter until at about the feed 95 water level the steam is produced and flows

through the return legs of the coils *g''* to 100 the upper part of the chamber *d*. The lat-

ter acts as a super-heating chamber, which 105 effect is considerably increased by the fire-

brick arched roof *c* which receives the direct 110 products of combustion, as they flow up-

wardly from the burner, and reflects the 115 heat downwardly around the upper legs of

the coil *g''* and along the upper side of the 115 water chamber somewhat after the manner

of a reverberatory furnace. The products 120 of combustion themselves are directed down-

wardly around the lower tube sections and 125 pass out of the generator at the rear.

Preferably the feed pipe *e* is arranged a 130 distance above the bottom of the water

chamber *d* in order that the water may free 135 itself of sediment which drops to the bottom

of the chamber and may be blown off 140 through the cock *j* (Fig. 1).

The usual safety valve, water gauge and 145 pressure gauge are arranged as shown and

require no description.

Steam is taken from the upper part of the 150 chamber *d* through pipe *k*, and preferably

led across the interior of the generator to 155 the opposite side as shown. If a further

degree of super-heat is required, the pipe *k* 160 may be arranged as a coil. In any event it

is carried to the outside of the generator and 165 provided with a pressure regulating valve

k', a check valve *k''* and suitable valve cocks 170 *k''*, *k'''* for a purpose to be described. The

pipe *k* re-enters the generator at approxi- 175

mately its middle and is provided with a 180

185

downwardly directed constricted nozzle k^5 which enters the tube m^9 through which the oil vapors are led to the super-heater D. The nozzle k^5 acts on the injector principle to accelerate the flow of oil vapors (whose production is to be explained) and forms a mixture of steam and oil vapor (hereinafter referred to as the "mixture") which passes through the super-heater.

10 Before referring to the construction and operation of the super-heater D, I will describe the course of the crude oil which is fed into the apparatus, its partial or entire purification, and its vaporization, all of which occur prior to the time that the oil vapor is combined with the steam injected into it through nozzle k^5 . Crude oil is fed into the device through valve or valves m (shown at the right in Fig. 1) and enters a series of oil preheaters which are in the form of pipes m^2 having vertical sections and approximately horizontal sections, which latter lead to the upper part of a purifying chamber m^3 . Any suitable number of tubes m^2 may be provided, twelve being shown as before indicated in Figs 4 and 5. In this case there may be twelve valves m , one connected with each tube m^2 , or preferably means are provided for regulating 20 the feed of oil accurately through these tubes, such means consisting of an automatic valve adapted to intermittently deliver fixed quantities of oil to the various tubes, such valves being adjustable to regulate the quantities delivered. The provision of a valve of this type is important in that it is preferably power-operated, accurately regulates the feed, and delivers the oil intermittently. It will be described 30 later as its operation is not essential to an understanding of the operation of the oil preheaters.

45 It will be noted that oil enters the various tubes m^2 at points considerably above their lower ends. These tubes are heated at their lower ends by the descending current of the products of combustion, so that when the oil enters each tube through the intermittent valve mechanism it is subjected in a condition of rest to the influence of heat which causes it to throw out a portion of the heavy matters which it contains. The speed of feed is regulated so as to deliver to each 50 tube such quantity of oil as will be completely vaporized in its passage through the horizontal part of the tube. The oil hence enters the oil chamber m^3 from each of the tubes m^2 in the form of vapor. This chamber m^3 is preferably constructed as shown in Fig. 5, that is to say, with an inclined lower wall m^6 leading to a pocket m^7 at one end of the chamber. The oil vapors entering the chamber from the various tubes m^2 are permitted to expand in this

chamber, and during such expansion the vapors rid themselves of still further quantities of impurities or other heavy matters, while the chamber is so shaped in proportion that the vapors do not become sufficiently cold to condense back to liquid. The impurities flow down the inclined wall m^6 and collect in the pocket m^7 . A certain proportion of the heavier matters and impurities are abstracted by this operation, 70 and the oil vapor passes out of the chamber m^3 through passage m^8 (Figs. 5, 6,) which passage is connected with pipe m^9 as best seen in Figs. 1, 6.

As before stated, the steam injector 80 nozzle k^5 projects into the tube m^9 and a thorough mixture of the steam and oil vapors takes place at this point. The tube m^9 is given a downward direction in line with the nozzle, so that a considerable acceleration of the speed of the mixture is produced at this point. The tube m^9 carrying the mixture connects with the lower of a series of coils n n' etc., constituting a 85 large part of the mixture superheater.

The arrangement of these coils n etc. is best shown in Figs 4 to 6. By reference to Fig. 6 it will be seen that starting from the tube m^9 the coil n is carried back and forth over the lower water coils g , resting upon the latter, and finally returns to a point near the beginning where it is dropped downwardly to a slight extent and enters chamber o . The next coil n' is also connected with the chamber o and passes back 90 and forth immediately over the coil n until at its end it enters the chamber o' . The remaining tubes of the series are similarly arranged, each starting in one of the tubes o o' , etc. and returning to the next chamber 100 o o' etc.

All of the coils are preferably given the same shape and lie one immediately over another, thus providing a series of clear passages p p' p^2 (see Figs. 4 and 6), through 110 which the products of combustion from the burner C rise to the upper part of the generator.

The function of the superheater is to progressively throw out or deposit the impurities contained in the oil vapors, which depositing action is considerably increased by the heat of the generator, and the action of the superheated steam. It will be observed that the pipe n enters the chamber 120 o at a point below the exit through the pipe n' , and preferably each incoming section delivers the mixture at a point lower than its exit through the next coil. Preferably each incoming section is provided with a 125 deflector or downwardly-turned portion (illustrated in detail in Fig. 7), whereby the incoming mixture is delivered in a downward direction, thus facilitating the deposit of the heavier matters. The vapors rising 130

to the top of each chamber are then passed out to the next succeeding section.

It will be noted that as the mixture passes through the succeeding coils and chambers it becomes progressively hotter, so that when it reaches the last chamber o^{10} (Fig. 5) it is in a highly heated condition. As the mixture enters each chamber o it is, of course, expanded considerably and at each expansion becomes further purified. As the mixture is hence increased in bulk it is desirable that the cubic contents of the various chambers o be also progressively increased, as illustrated in Fig. 5.

15 For simplification the chambers o o' etc. are preferably arranged in the hollow wall of the generator which corresponds to the chamber d on the water side of the generator. By this arrangement the walls of the 20 chambers (which preferably are of sheet iron or steel) are exposed to the downwardly descending products of combustion which assist in the process just described.

By the process and apparatus just described there is obtained in the chamber o^{10} a mixture of steam and oil vapor thoroughly freed from all heavy, carbonaceous and tarry matter, the mixture being super-heated to a high degree. For the purpose of refining 30 oils, however, the degree of heat is maintained below that which would change the vapors to a chemically fixed gas.

The chief function of the steam in the process just described is believed to be mechanical in its nature. It cleans and purifies the oil vapors, absorbs heat from the apparatus so as to prevent the same from becoming overheated, and accelerates the motion of the vapors by the action of the injector or constricted nozzle. Furthermore, it carries with it heat to the stills where the separating process or processes take place. When the invention is operated in connection with shale oil, it is practically necessary 40 to incorporate a certain quantity of alcohol into the mixture. This may be easily done by providing a coil q (Figs. 1 and 3) which runs over the uppermost steam section g^8 wherein the alcohol is gasified. The gaseous 45 alcohol is then led through a valve q' (Fig. 3) to the steam pipe k . Preferably this section is removably constructed, so that in case it is not used it may be removed bodily from the apparatus, whereby to prevent burning 50 out. The alcohol may be ethyl alcohol or other substances of the alcohol group.

In Figure 8 is illustrated a form of automatic rotary valve which has previously been designated by the reference letter m . 55 While other forms of valve may be adapted for the purpose, that illustrated is suitable. The valve m comprises a tubular casing r' having on one side a series of passages r^2 which connect with the various tubes or 60 pipes m^2 before referred to. One end of the

casing is connected with a source of oil under pressure through a pipe r^3 . The interior of the casing is bored, preferably with a tapered bore, within which turns a tapered valve member r^4 shown as open at its inner 70 end, or that end which is next to the oil inlet tube r^3 . The valve r^4 is provided with a number of passages r^5 corresponding to the passages r^2 in the casing, and so arranged that as the valve is rotated the passages r^5 75 will be brought successively into alignment with the passages r^2 . By this means oil is delivered to the tubes m^2 once (or any suitable number of times) during each rotation of the valve. When the passages are out of 80 alignment the tubes m^2 are closed and no oil flows into the same. The oil in each tube hence is given a period of rest or quietude during which it may become heated and deposit a part of its solids at the same time. 85

The opposite end of the casing r' is provided with a cap r^6 through which passes a shaft r^7 , a stuffing-box being provided as shown. The inner end of the shaft is fixed to the valve r^4 , while the outer end thereof is 90 provided with some means for receiving rotary motion, such as a sprocket or gear r^8 . This may be driven from any suitable source of power, not shown. It is desirable, however, that the speed of rotation of the valve 95 r^4 be capable of variation. To this end the gear or sprocket r^8 will be properly proportioned with relation to its driving element, or a frictional or other variable speed mechanism may be employed for this purpose. 100

It is preferable, as before stated, that the speed of rotation of the valve and the dimensions of its parts r^5 , be so proportioned relatively to the pressure of oil flowing into the valve through the pipe r^3 , that each tube m^2 105 shall receive in a given time only such a quantity of oil as will be vaporized in the horizontal portion of the tube.

It is desirable that the residue or more or less solid matters which have been dropped out of the oil into the pocket m^7 and the respective chambers o o' , etc., be automatically discharged from the oil side of the generator. This is preferably done by means of an automatic valve in all respects 110 similar to that illustrated in Fig. 8, and just described, except that the flow through the valve is in a reverse direction. In Figures 1 and 6 s indicates the valve driven by a suitable sprocket or other device s' , and which is connected with the various chambers or pockets by short lengths of tube s^2 , a regulating cock or valve s^3 being introduced in each tube. At the end of the valve 115 is an outlet, also controlled by a cock s^4 . The residue in each of the chambers above-mentioned, being under considerable pressure due to the vaporized products above it, is forced out at regular intervals into the cylindrical valve and through the bore of the 120

latter outwardly to any suitable receptacle through the cock s^4 . If the character of the oil being used is such that it is desirable to keep separate the residuum products from any particular chambers, say m^7 , o , o' and o^2 o^3 o^4 , etc., for subsequent treatment such as the recovery of asphalt from some of them for instance, separate automatic valves are used, each having a sufficient number of ports corresponding with as many chambers as desired to connect together, each valve operated by a separate sprocket wheel, but receiving their motion from same medium and having same speed.

15 Referring now to Figure 5 of the drawings, it will be observed that the last of the tube sections n n' etc. on its return leg enters the last chamber o^{10} and delivers to it substantially pure oil vapors mixed with steam.

20 If in the number shown, operating with a given class of oil, this result is not reached, the number of chambers and tubes may be increased as desired. The mixed vapors are now ready to pass into the system of condensers and an opening n^{11} is provided in the upper part of the chamber o^{10} through which the mixed vapors pass into a tube n^{12} (Fig. 9) controlled by a valve n^{13} to the condensers.

30 The general character of condenser which is preferred is illustrated in Figure 9. The body is shown as a cylindrical structure t , the upper section of which is surrounded by a water jacket t' to which water is fed 35 through a pipe t^2 passing past a thermostatic valve of common construction t^3 , and into the jacket through an inlet tube t^4 . The upper part of the water jacket is provided with an outlet pipe t^5 through which

40 heated water is discharged. At the lower part of the condenser a similar jacket t^6 is provided for the reception of superheated steam, or other heating fluid which flows in through a pipe t^7 past a thermostatic valve t^8 and into the jacket through an inlet tube t^9 . The condenser steam in the jacket t^6 passes down a valved tube t^{10} into a steam trap of common construction t^{11} , whence it flows into the return line.

50 By means of the two jackets thus described it is obvious that there may be formed in the condenser two zones of heat, the upper zone being preferably the cooler one and the lower zone the hotter one. The temperatures in these two zones may be controlled accurately by the thermostatic valves which admit the water and the steam respectively to the jackets.

60 Reserving other features of construction of the condenser to be described later, it is to be noted that the mixed vapors entering through the pipe n^{12} pass into the top of the condenser through a vertical pipe n^{20} which is closed at its lower end, and provided with a series of holes adjacent thereto designated

by the letter n^{14} . At the lower end of the pipe n^{20} is arranged a basket n^{15} or other support for a body of glass wool or slag n^{16} . The result of this construction is that as the mixture is discharged into the condenser it is distributed outwardly striking the inner wall of the condenser in a series of streams or jets, and being under pressure passes upwardly through the glass wool or slag. At the temperature and pressure maintained 70 the lighter vapors rise, filter through the glass wool or slag and pass up to the top of the condenser which has an enlarged outlet t^{12} surrounding the inlet pipe n^{20} , through which outlet the lighter gases or vapors pass, 80 to the outlet pipe t^{13} to the next condenser.

In the first condenser of the system the temperatures and pressures are so proportioned that practically all of the hydrocarbons pass out from the condenser to the second condenser, excepting the heaviest lubricating oils and wax. It is desirable to provide means for automatically removing these products, as well as the steam which condenses in the condenser. The bottom of the condenser below the steam jacket is somewhat cooler than the jacketed portion, and the water of condensation hence collects in the bottom. The means employed for automatically draining the condenser comprises an automatic valve t^{14} . This valve is connected with a sediment pocket t^{15} depending from the lower part of the condenser as shown (which has a hand-operated cock t^{16} by which the sediment may be drawn off), the connection being preferably through a horizontal pipe t^{17} which may have a hand-operated valve t^{18} to determine the flow through the pipe.

The automatic valve t^{14} comprises a casing t^{19} in which operates a float t^{19} which controls a discharge valve t^{20} through the medium of a lever arm t^{21} and connecting link and valve stem t^{22} . The particular construction of this valve need not be described, since any suitable valve may be used. The casing of the valve t^{14} is connected at its upper end with a pipe t^{23} which leads through the steam jacket t into the interior of the condenser.

The respective liquid levels in the condenser are indicated by the lines x x and x' x' , the former being the oil level which it is desired to contain, and the latter being the water level. When the oil reaches its level it flows through the pipe t^{23} into the top of the casing, and the water of condensation flows through the pipe t^{17} into the bottom of the casing, until it reaches the level x' x' . The casing is hence (after starting) always maintained substantially full of oil and water, but the float t^{19} is so balanced that it is supported by the water, and not by the oil.

The operation, so far as the passage of the

water is concerned, is as follows:—When the water level increases beyond the line $x' x'$, the float t^{19} is raised and the valve t^{20} opened. The water of condensation passes out through the valve to the return line 325 until the water level falls to the line $x' x'$, when the valve is closed.

The heavy lubricating oils, etc. which are condensed in the condenser are led out of the same through the pipe t^{23} and continuation thereof t^{24} to a common form of trap t^{25} . From this trap the oil (which is still very hot), is preferably led to supplementary condensers, which may advantageously form also feed water heaters for the steam generator. Except in so far as the different quantities of oil may be present in the automatic valve t^{14} , the oil is discharged in the same proportion as it is formed. Nevertheless, there remains in the bottom of the condenser a considerable body of oil near its vaporizing point, which oil is utilized (especially in the later condensers whose operation is yet to be described) to increase the yield of the lighter hydrocarbon products and decrease the yield of the heavier products.

The construction and operation just described is practically repeated in the first four or five condensers, and in many cases it is not necessary to utilize the water jacket in these condensers, since as the condensers are exposed to the atmosphere on their outer sides, the cooling effect of the atmosphere will usually suffice. In the successive condensers of the first group of four or five successively lighter lubricants will be deposited in the bottom and drawn off as described.

The condensers operate mainly by difference in temperature. That is to say, if the temperature of the body of the condenser is maintained at a given degree of heat, it is obvious that to a large extent those constituents of the mixed vapors introduced into the condenser, whose points of liquefaction lie above that of the condenser, will liquefy and drop out of the mixture, while those constituents which lie below that of the condenser will remain gaseous and pass to the next condenser. It is obvious also that the pressures which are maintained have an effect in determining the liquefaction of the gases. It is preferred to operate the first condenser in such manner that the heaviest lubricating oils and wax will be deposited, while the succeeding few condensers have their temperatures so controlled that successively lighter lubricants will be deposited. For instance, the lightest of the lubricants, or spindle oil, amber in color, has been obtained from the fifth condenser. It is obvious, however, that this method of operation may be changed if

desired. The temperatures and pressures hence grow gradually lower as the vapors pass along the battery.

After the lubricating oils have been obtained from the mixed vapors, say for instance, at the sixth condenser, the vapors will contain the kerosenes, naphthas, gasolines and other lighter products. Assuming that at the sixth condenser it is desired to commence the withdrawal of these lighter products, the temperature of this condenser will, as before, be maintained slightly lower than the fifth, but still higher than the normal gasifying points of all of the constituents except, let us say, kerosene. At this condenser it is advisable to circulate water through the water jacket, since by this time the temperatures have become lowered and it is desirable to have a more easily-controllable temperature in the upper part of the condenser than is obtained by the atmospheric air. The vapors entering the sixth condenser are hence partially condensed, the heavier product dropping to the bottom, and in normal operation into the body of oil contained at the lower part of the condenser. This body of oil is maintained quite close to its gasifying point, while the condensed oils from the top of the condenser are somewhat cooler in temperature. It is found in practice, as a result of this method of operation, that the condensed hydrocarbons undergo a dissociation into specifically lighter hydrocarbons of lower boiling point. This being repeated in the successive condensers produces an extremely large yield of the lighter and more valued hydrocarbons. In operation it is found that the residuum in the sixth condenser may be an intermediate or gas oil of a straw color, which is a valued oil for fuel, and which may be classified among the kerosenes. The product obtainable from the seventh condenser is a distinct kerosene of light, straw color, and the eighth and ninth condensers also produce kerosene of lighter gravity but perfectly water-white or crystal. As before stated, the yield of these condensers, if operated according to the preferred form of the invention, is not in amount the kerosenes which have deposited in the condensers, but a considerable portion of these kerosenes is broken up so that the yield in the succeeding condensers of hydrocarbons of lighter gravity is increased.

A very notable and important feature of the operation of the invention lies in the fact that the products obtained, and especially those from the medium lubricating oils on to the very lightest products, are clean, pure, and of sweet odor, and require no specific chemical treatment or purifying. A remarkable feature of the invention is

- that by its operation I am enabled to obtain many hydrocarbon products which are not chemically classified. Analysis shows that these products are pure hydrocarbon products, but they appear to lie between the recognized classes of products. Some of them are of great commercial value. Another important feature of the invention is that by which I am enabled to obtain a maximum yield of the lighter and more valuable products used in the industries and arts, which is far in excess of the proportion obtained in any distilling or refining system with which I am acquainted. A further important feature of the invention is the fact that I am able to obtain what may be termed synthetic products not heretofore obtained by any system with which I am familiar.
- It is particularly desirable that the generator A first described in this specification shall have its heating means under accurate control. Such a heater has been previously referred to as the burner C. It forms no essential part of the present invention however, and need not be described in detail.
- While certain methods have been described for refining oil and certain apparatus by which these methods may be practiced, it will be understood that these are capable of wide variation without departing from the invention. It will also be understood that the number of stills B may be many, as desired. In practical operation from 20 to 40 stills are useful. The mechanism described may also be widely varied without departing from the invention. It will be understood that many variations and changes may be made in the structure and process and products hereinbefore described without departing from the invention.
- What I claim is:
1. The method of refining oil which consists in completely vaporizing the oil by heat, partially purifying the oil vapors by a series of expansions and re-heatings, forming a mixture of steam and such partially purified oil vapors, further purifying the mixture by a succession of expansions and reheatings, and subjecting the mixture to different temperatures and pressures to condense products therefrom.
  2. The method of refining oil which consists in completely vaporizing the oil by heat, partially purifying the oil vapors by a series of expansions and reheatings, forming a mixture of steam and such partially purified oil vapors, further purifying the mixture by a succession of expansions and reheatings, and subjecting the mixture to successively lower temperatures whereby to condense from the mixture a series of hydrocarbon products of successively lower liquefaction points.
  3. In apparatus for refining oils, the combination of means for vaporizing the oil, means for purifying the oil vapors, means for forming a mixture of partially purified oil vapors and steam, means for further purifying the mixture, said means being arranged to communicate with one another in succession in the order stated, a plurality of condensers adapted to condense different products from the mixture, means for maintaining different temperature zones in said condensers, said means adapted to produce a colder zone above a hotter zone, and means for introducing the mixture between said zones.
  4. In apparatus for refining oils, the combination of means for vaporizing the oil, means for purifying the oil vapors, means for forming a mixture of partially purified oil vapors and steam, means for further purifying the mixture, said means being arranged to communicate with one another in succession in the order stated, a plurality of condensers adapted to condense different products from the mixture, means for maintaining different temperature zones in said condensers, said means adapted to produce a colder zone above a hotter zone, means for introducing the mixture between said zones, and means for filtering the incoming mixture.
  5. In an apparatus for refining oils, the combination of a condenser having a single chamber, means for introducing oil vapors into said condenser, means for maintaining zones of different temperatures in said chamber, and means for collecting the condensation product therein.
  6. The method of refining mineral oils which consists in forming a mixture of oil vapors and steam, introducing alcohol into the mixture and condensing the mixture.
  7. The method of refining shale oil which consists in vaporizing the oil, forming a mixture of oil vapors and steam, introducing alcohol into the mixture of vapor formed, and condensing from the mixture the product desired.
  8. The method of refining shale oil which consists in vaporizing the oil, forming a mixture of oil vapors and steam, introducing alcohol into the mixture of vapor formed, and condensing from the mixture a series of products of a given liquefaction point.
- In witness whereof, I have hereunto signed my name in the presence of two subscribing witnesses.
- RAYMOND AUGUSTE DORNÈS.
- Witnesses:
- EUGENE R. MYLES,
FRED WHITE.
